UNITED STATES PATENT OFFICE.

WILLIAM V. ROBINSON, OF DETROIT, MICHIGAN.

GRINDING OR POLISHING MACHINE.

1,114,809.

Specification of Letters Patent. Patented Oct. 27, 1914.

Application filed May 31, 1913. Serial No. 770,969.

To all whom it may concern:

Be it known that I, WILLIAM V. ROBINSON, a citizen of the United States of America, residing at Detroit, in the county of Wayne and State of Michigan, have invented certain new and useful Improvements in Grinding or Polishing Machines, of which the following is a specification, reference being had therein to the accompanying drawings.

My invention relates to grinding or polishing machines.

The invention resides in the novel means for effecting a proper, relative movement between the grinder or polisher and the article to be operated on; in the means for effecting an automatic, relative adjustment between the work and the grinder or polisher; in the producing of a structure in which the grinder or polisher is driven at a uniform speed and also the relative movement between the grinder or polisher and the work is uniform; in the relation and construction of the traveling carriage and frame; in a device for retaining the work in proper relation to the grinder and in a means for avoiding over grinding of the edges or extremities of the work; further in certain constructions, arrangements and combinations of parts as will more fully hereinafter appear.

In order that the invention may be better understood I will show and describe the same as embodied in a machine of the type employed for grinding or polishing stove parts, though I do not desire to limit my protection to the particular device illustrated.

In the drawings,—Figure 1 is a perspective view of the machine embodying my invention; Fig. 2 is a side elevation thereof; and Fig. 3 is an end elevation. Figs. 4 and 5 are views at right angles illustrating the work container; Figs. 6, 7 and 8 illustrate certain details of construction; and Fig. 9 is a fragmentary top view partly in section of the structure shown in Figs. 4 and 5.

A designates the main frame having a longitudinally-extending track B upon which is arranged a second frame C having wheels D traveling upon the track B. The latter and the frame C are preferably formed of angle iron. The sides E of the frame C form tracks for the wheels F of the carriage G which is adapted to support the work. The members C and G are mounted for

travel at right angles to each other and the work therefore, is mounted to be moved longitudinally upon the traveling of one of the carriages, and to move laterally upon the actuation of the other carriage.

H is a grinder positioned in operative relation to the work-support G, and as the work in the device illustrated is adjusted in relation to the grinder by the actuation of the carriages, the grinder is held stationary, as far as lateral and longitudinal movement is concerned.

The frame C is reciprocated backward and forward upon the track B and this reciprocation is continuous and the reversing effected automatically. Thus, mounted in a suitable bearing I in the main frame is a shaft J driven through the medium of a pulley K. Secured to the shaft J is a sprocket L which is connected by means of a chain M with a second sprocket N carried upon a shaft O that is mounted in a suitable bearing as P on the main frame. The bearings I and P are fixed in relation to the main frame and the shaft J is continuously driven.

Q is a member depending from the frame C and provided with an elongated, vertically-arranged slot R within which is positioned a projection or pin S attached to the chain M. By this arrangement, when the pin S is passing intermediate the sprockets and below the same, the frame C will be moved in one direction, and when the pin passes between the sprockets at the top thereof, the frame will be moved in the opposite direction. The pin is of course, so arranged as to freely pass around the sprockets, and the slot R will allow the pin to pass from beneath the sprockets to thereabove.

During the longitudinal reciprocation of the frame C the polisher or grinder will operate upon the work longitudinally thereof. Therefore, when the work reaches the limit of its longitudinal travel, the carriage G is moved a given distance laterally, and preferably this lateral shifting of the carriage G is accomplished at both limits of the longitudinal travel of the frame C. As shown, the member G has secured to the bottom face thereof a rack T provided with two series of teeth U V, adapted to be engaged by a dog W pivoted at X to a support Y on the frame C. Suitably connected to the carriage G is a cable A' adapted to

be wound upon a drum B' fixed to a shaft C' in the frame C.

D' is a second cable fixedly connected to the shaft C' and having a weight E' tending to rotate the shaft in a direction to wind up the cable A' and move the work-support G toward the shaft C'. However, when the dog W is in engagement with the teeth on the rack-bar, it will hold the carriage G against actuation through the medium of the cable A'. The dog W is actuated in one direction when the frame C reaches the inward limit of its movement, and in the opposite direction when this frame is at its outward limit, and the teeth U and V are arranged in alternate relation so that the movement of the dog will release the same from its engagement with one of the series of teeth or racks and permit the carriage G to be moved laterally by the cable A' a slight distance before the dog engages with the teeth on the other rack. By spacing the teeth on the rack, any suitable lateral movement of the carriage C may be provided.

Preferably the dog W is actuated through the medium of a sliding rod G' having its inner end pivotally connected at H' to the dog W and having its outer end carrying a downwardly-extending arm I' which is adapted to engage a trip J' when the frame C reaches its outward limit of movement, and to contact with a second trip K' at the inward limit of the frame C. The trips J' and K' are so arranged that they will engage the arm I' slightly in advance of the limit of travel of the carriage G, so as to arrest movement of the rod G' before the limit of movement of the carriage is reached, thereby causing a shifting of the dog relative to the racks, as the carriage continues to its limit of travel.

The grinder or polisher H is herein shown as of circular form and is mounted upon a shaft L' carried by a frame M' pivotally secured to a shaft N', journaled in supports or standards O' in the main frame. The shaft L' is driven from the shaft N' through the medium of pulleys P' Q' and belt R'. The shaft N' forms the main drive shaft and the shaft J is actuated therefrom by step-down drive trains R⁴ R⁵ and a drive train R⁶, as will be readily apparent upon reference to Fig. 2. The frame M' is connected to the outer end of a member S' which is fulcrumed intermediate its ends upon a suitable support T' on the main frame, and has its other end attached to a counter-weight U', the counterweights serving to off-set to the desired degree the weight of the grinder or polisher.

It is desirable to provide means for raising the grinder out of engagement with the work, and I therefore, attach the frame M' by means of a connection V' to a lever W'.

This lever is fulcrumed at X' to a support Y' on the main frame and the outer end of this lever engages an elongated eye Z' in a rod A² attached to the main frame. The eye Z', as will be apparent upon reference to Fig. 3, will permit movement of the lever W' in a direction to raise the frame M', but this loop is so arranged that it will limit the upward movement of the outer end of the lever W' and therefore, limit the movement of the grinder or polisher toward the work. The grinder or polisher is however, free to raise. To allow of adjusting the distance of the grinder from the carriage G the connection V' is preferably provided with a suitable turn-buckle C². D² D⁴ are co-operating catches for holding the lever W' in its adjusted position when it has been moved to raise the frame M'.

In the operation of the device heretofore described, the work is placed upon the carriage G and the latter moved to the outward limit of its lateral movement, or away from the shaft C', the dog W engaging the rack-bar and preventing return of the support G. The frame C' is then arranged at one limit of its longitudinal reciprocation and power applied to the shaft R', which will drive the grinder or polisher and also actuate the chain M. During the travel of the frame C along the track B a longitudinal strip of the work will be polished equal to the width of the work surface of the member H. When the frame C reaches the limit of its movement the carriage G will be shifted laterally and during the travel of the frame C in the opposite direction the member H will polish another longitudinal strip. The lateral shifting of the carriage G is of course, so proportioned that all parts of the surface of the work will be acted upon by the grinder or polisher. Furthermore it is to be noted that the grinder is driven at a constant rate of speed and that all parts of the work are acted upon by the grinder or polisher for the same length of time. This insures uniform grinding of the surface being worked upon.

In polishing or grinding certain articles, particularly where there are movable parts, I find it desirable to provide means for retaining the work in desired relation to the table. This is especially so in grinding or polishing stove tops where the lids are in place. The retainer may be of various constructions but in Fig. 1, I have illustrated a device of novel construction and which is particularly adapted for this purpose. Thus D² is a stove top having the usual lids, E² and F² is the retaining member, in the form of a carriage G² provided at opposite ends with rollers H² adapted to engage the work and having their axes at right angles to the travel of the carriage G upon the frame C. The retainer F² is attached to a

member I^2 extending transversely of the carriage G and spaced from the upper face thereof.

J^2 K^2 are supports fixedly connected to the traveling frame C at opposite ends thereof and to the upper ends of which the member I^2 is attached. The carriage G^2 is so connected to the member I^2 as to be yieldingly held in engagement with the work.

This is preferably accomplished by attaching the member G^2 to the cross-bar or member I^2 by means of headed bolts L^2 M^2 fixedly secured to the member I^2 and having their upper ends slidably engaging apertures N^2 in the cross-bar. This allows the carriage G^2 to move vertically, and the apertures N^2 are of sufficient size to permit the carriage to have a slight longitudinal tilting. O^2 is a leaf-spring serving to yieldably press the member G^2 downward, or in a direction to engage the work. One end of this spring is connected to the bottom face of the cross-bar I^2 as by means of rivets P^2 , and the opposite end rests upon the top of the member G^2 and is slotted at Q^2 R^2 to receive the bolts L^2 M^2 . Preferably two of these retainers are employed, and the cross-bars carrying the same are arranged upon opposite sides of but in proximity to the grinder or polisher H and therefore, the work is yieldably held in engagement with the member G at points upon opposite sides of the grinder, preventing accidental tilting of the work during the grinding or polishing operation.

When the wheel H reaches the edges of the work, if the edge travels beyond the vertical plane passing through the center of the wheel, the latter will drop down a slight distance, sufficient to grind off the edge as a . To avoid this, means is provided which will prevent the member H from dropping over the edges. Preferably this is accomplished by arranging guards b c at the opposite limits of longitudinal travel of the wheel H in relation to the work-support and attaching to the carriage M' a shoe d having inclined or cam faces e f adapted to engage respectively the guards b c . The latter are formed of members each having one end attached to one of the sides E of the carriage C and having its upper end terminating in a laterally-extending flange g . In order to properly adjust the shoe d in relation to the work upon the support, the shoe is adjustably connected to the frame M' as by means of screws h engaging elongated slots i in the shoe. By the arrangement just described, when the member H reaches the edge a , the portion e will engage the flange g and prevent the grinder from dropping down. Similarly when the grinder reaches the inner edge of the work the portion f will engage the member c . The member D is of course, so adjusted that when the portions

e f are in engagement with the flanges g the grinder cannot be dropped below the horizontal planes of the opposite edges of the work.

What I claim as my invention is:—

1. In a grinder or polisher, the combination with a frame, of a carriage mounted thereon for reciprocation, a support arranged upon said carriage, means tending to move the support in one direction, a rack and dog for producing a step-by-step movement of the support in said direction, means for producing a relative movement between said dog and rack, arranged upon said carriage, and a trip for said means positioned to engage the latter slightly in advance of the limit of reciprocation of said carriage.

2. In a grinder or polisher, the combination with a frame, of a carriage arranged thereon for reciprocation, a support mounted on said carriage, means tending to move said support in one direction, means for effecting a step-by-step movement of the support in said direction, an operating member for said means arranged upon said carriage, and trips acting upon said operating member at the opposite limits of reciprocation of said carriage.

3. In a grinder or polisher, the combination with a support, an operating member positioned in operative relation to the support, a lever, a connection between said lever and said frame, and means cooperating with said member to limit the movement of the member toward the support.

4. In a grinder or polisher, the combination with a work-support, an operating member positioned in operative relation to the support, and means independent of the work support positioned in proximity to said operating member for preventing accidental movement of the work relative thereto.

5. In a grinder or polisher, the combination with a work-support, an operating member positioned in operative relation to the support, and means extending over the support and positioned in proximity to the operating member for preventing accidental movement of the work relative to said member.

6. In a grinder or polisher, the combination with a support, of a carriage over which said support is adapted to move, an operating member positioned in operative relation to the support, a cross-bar carried by the carriage, and means connected to said cross-bar for exerting a yielding pressure upon the work.

7. In a grinder or polisher, the combination with a support, of a carriage over which said support is adapted to move, an operating member positioned in operative relation to the support, cross-bars carried by the carriage and arranged upon opposite sides of

- the work-operating member and in proximity to the path of movement thereof, and yielding means carried by said cross-bars for exerting a pressure upon the work.
5. 8. In a grinder or polisher, the combination with a support, of a carriage over which said support is adapted to move, an operating member positioned in operative relation to the support, members extending upwardly from the carriage at opposite ends of the support, a cross-bar connecting said members, a roll connected to said cross-bar for vertical play, and a spring attached to the cross-bar and adapted to exert a pressure 10 on said roll in the direction of the support.
9. In a grinder or polisher, the combination with a work-support, of a member for operating upon the work adapted to move toward the carriage, means for reciprocating the carriage, and means for limiting the movement of said member toward the work at a predetermined point in the travel of 15 said carriage.
10. In a grinder or polisher, the combination with a work-support, of a member for operating upon the work adapted to move toward the carriage, means for reciprocating the carriage, and means for limiting the movement of said member toward the work 20 at one limit of reciprocation of said carriage.
11. In a grinder or polisher, the combination with a work-support, of a member for operating upon the work adapted to move toward the carriage, means for reciprocating the carriage, and means for limiting the movement of said member toward the work 25 at the opposite limits of reciprocation of said carriage.
- 40 12. In a grinder or polisher, the combination with a reciprocating carriage, of a member for operating upon the work on the carriage, adapted to move toward the carriage, a guard arranged at one end of the carriage, and a shoe operatively attached to said member for engaging said guard at a predetermined point in the travel of said carriage.
13. In a grinder or polisher, the combination with a reciprocating carriage, of a frame adapted to rock toward the work, a work-operating member carried by said 50
- frame, guards arranged at opposite ends of said carriage, and a shoe attached to said frame and adapted to engage said guards. 55 for the purpose described.
14. In a grinder or polisher, the combination with a work support of means independent of the work support for yieldably pressing the work toward the support. 60
15. In a grinder or polisher, the combination with the work support of a traveling carriage for carrying said work support, and means on said carriage for yieldably pressing the work toward the support. 65
16. In a grinder or polisher, the combination with a support, an operating member positioned in operative relation to the support, a lever, a rod attached to said frame, and coöperating catches respectively on said 70 rod and lever to limit the movement of the member toward the support.
17. In a grinder or polisher, the combination with a reciprocating carriage, of a transversely-moving work-support, a member for operating upon the work, and means for limiting the transverse movement of said work-support at a predetermined point in the travel of said carriage. 75
18. In a grinder or polisher, the combination with a reciprocating carriage, of a transversely-moving work-support, a member for operating upon the work, a lever, an adjustable connection between said lever and said support, and means coöperating with 80 said carriage to limit the transverse movement of the support.
19. In a grinder or polisher, the combination with a frame having a track, a carriage having wheels mounted thereon, said carriage being provided with a track at substantially right angles to the first-mentioned track, a work-support having wheels mounted upon said carriage track, automatic means for continuously reciprocating said carriage, and means for automatically effecting a step-by-step movement of the support at each stroke. 85
